A. H. HAAG

RADIOCABINET

Filed Feb. 27, 1925

Fig. 3.

Alfred H. Haag, INVENTOR:

BY
Medesheug Janbarts.
ATTORNEYS.

UNITED STATES PATENT OFFICE.

ALFRED H. HAAG, OF BALTIMORE, MARYLAND, ASSIGNOR OF FIFTEEN ONE-HUNDREDTHS TO E. HAYWARD FAIRBANKS, OF MERCHANTVILLE, NEW JERSEY.

RADIOCABINET.

Application filed February 27, 1925. Serial No. 11,998.

To all whom it may concern:

Be it known that I, ALFRED H. HAAG, a citizen of the United States, residing at Baltimore, in the county of Baltimore City, State of Maryland, have invented a new and useful Radiocabinet of which the following is a specification.

My invention relates to a novel construction of a radio-cabinet, wherein I make provision for an angular front recess for supporting the radio-cabinet or panel, which is usually highly finished and of an ornamental appearance, where it will be readily visible and at the proper height to enable the operator when sitting to manipulate the controls in tuning in, said table being also provided in the rear at a point above the radio with a hood or amplifier enclosure, which conceals the loud speaker in the rear thereof, the rear of the table not only being adapted for the reception and concealing of the loud speaker, but also for the reception and concealing of the A and B batteries, commonly employed.

It further consists of a novel adjustable support in the rear of the radio-cabinet, whereby any of the conventional sizes of the loud speaker or amplifier elements can be adjusted vertically so as to position the exit of the loud speaker at the proper height with respect to the grille or exit of the loud speaker hood.

In the above ends, my invention consists of a novel radio-cabinet having a front, above which is the grille or exit for the radio productions behind which is the open space for the loud speaker and its adjustable support, while on either side of the latter are the battery compartments, all the space in the rear being open and readily accessible at all times.

It further consists of other novel features of construction and advantage, all as will be hereinafter fully set forth and pointed out in the claims appended hereto.

For the purpose of illustrating my invention, I have shown in the accompanying drawings forms thereof which are at present preferred by me, since they have been found in practice to give satisfactory and reliable results, although it is to be understood that the various instrumentalities of which my invention consists can be variously arranged and organized and that my invention is not limited to the precise arrangement and or-

ganization of these instrumentalities as herein shown and described.

Figs. 1 and 2 represent front and rear perspective views respectively of a radio table embodying my invention. Fig. 3 represents a perspective sectional view of a modification.

Similar numerals of reference indicate corresponding parts.

Referring to the drawings:

In carrying out my invention, I support my novel radio-cabinet 1, upon two front legs 2, which are shorter than the rear legs 3, and provide the side panels 4, which are of angular shape, and are dovetailed, rabbeted, or otherwise secured to said legs, 5 designates the front horizontal radio supporting shelf, 6 the rear wall and 7 the horizontal top, said radio shelf 5 being positioned at the top of the front legs and the top members 7 being coincident with the top of the rear legs whereby a front angular radio receiving recess is produced. Upon the center of the top 7, I position the loud speaker dome inclosure or hood 8, which is open at its rear and provided with the front preferably removable grille 9, the top 10, and the side walls 11, which at their junction with the top 7, are provided with the front corner brackets 12, which give a finished and ornamental appearance to the upper portion of the table.

The entire rear of the table 1 is preferably open and provided with the horizontal bottom wall 13, which supports the parallel vertical walls 14, which are provided with the inner aligning horizontal ways 15, in which slides the adjustable loud speaker shelf or support 16, on which rests the base of the horn for loud speaker 17 whose exit 18 is positioned at the rear of the grille 9. In the large chamber 19 formed between the bottom 13, the sides 4 and the top members 7, there is provided ample space for the A and B batteries 20 and 21 and the connections to the radio receiving apparatus supported on the front ledge or shelf 5, can be readily made through the openings 22 in the front vertical wall 6. The front drawer 23 is for the ear phones, radio log and records. As the cabinets or panels of most radio receiving sets are ordinarily in a highly finished and attractive condition, it is not necessary or desirable to conceal them and

they can be exposed and placed on the support 5, where the controls are at a readily accessible height for tuning in. The horn or loud speaker 17, can be readily installed 5 upon its shelf or support 16 and adjusted so that its exit will be at the desired height with respect to the grille 9, and the wiring connection common to the batteries and radio can be readily made through the openings 10 22 in the vertical wall 6. The batteries and loud speaker elements while entirely concealed from the front are readily accessible from the rear for inspection, adjustment and repairs which rear space I preferably leave 15 open as seen in Fig. 2, since the back of the table is ordinarily pushed against the wall. One standard sized table is adaptable for any radio set, which latter is visible and accessible and the loud speaker hood conceals 20 the amplifier and the rear adjusting device therefor. The device is adaptable to any size or make of amplifier, whose exit is positioned above the radio at the right height, so that the ear of the operator when 25 sitting is about on a level with said exit, there being plenty of leg room for the sitting operator underneath the table.

By my novel invention, I dispense with 30 all doors, and the expense of hinges and other hardware, as well as the attendant expense of fitting the same in position.

It will be observed from Figure 2 that the top edges of the upright walls 14 serve 35 to support the inner ends of the horizontal tops 7, so that a very rigid and durable structure is produced.

In the construction seen in Figure 3, I 40 have shown the drawer 24, as at one side of the front, and have shown a built in amplifier or loud speaker 25, having its exit end 26 positioned within the dome or hood 8, while its inlet end 27 carrying the unit 28 is positioned in the front wall 29, so that 45 the adjustable member as 30 of the unit is positioned at a conveniently accessible point just below the radio controls.

It will now be apparent that I have devised a novel and useful radio apparatus table which embodies the features of advantage enumerated as desirable in the 50 statement of the invention and the above description, and while I have, in the present instance, shown and described a preferred embodiment thereof which will give in practice satisfactory and reliable results, 55 it is to be understood that such embodiment is susceptible of modification in various particulars without departing from the spirit or scope of the invention or sacrificing any of its advantages. 60

Having thus described my invention, what I claim as new and desire to secure by Letters Patent, is:—

1. A radio cabinet, comprising a main body portion having an upstanding cabinet section surmounted thereon, a fixed horizontal table section extending forwardly from the base of said body portion, the said body portion, cabinet section and table section being open at the rear and closed at the top, front, 70 end and bottom portions thereof to form a single open compartment in the rear of said cabinet, a shelf for said body portion, means for vertically adjusting said shelf to accommodate horns of different heights, and a 75 grille in the front of said cabinet section.

2. A radio cabinet, comprising a main body portion having an upstanding cabinet section surmounted thereon, a horizontal table section extending forwardly from the base of said body portion, the said body portion, cabinet section and table section being adapted to be open at the rear and being closed at the top, front, end and bottom portions thereof to form a compartment in the 80 rear of said cabinet, a horn support in said compartment, means whereby said support may be adjusted to accommodate horns of different heights, and a sound exit at the upper portion of said upstanding cabinet section. 85

ALFRED H. HAAG.
